MICROTOME

Charles E. Soderquist, Jr., Chicago Heights, Ill., assignor, by mesne assignments, to Instrument & Development Products Co., a corporation of Illinois

Application March 29, 1955, Serial No. 497,670

2 Claims. (Cl. 88—40)

The invention herein described is a new type of ultra-microtome, designed to give sections of sufficient thinness to allow them to be used in electron microscopy.

Until the present time, most feed mechanisms for such devices depended upon various types of advancing motions which were lubricated by oil films. These films are extremely variable and when sections to be cut are of the range of size where variations in oil films are greater than the thickness of the cut sections, serial sections of uniform size are impossible to obtain.

The development of this microtome has two basic aims;

(a) to eliminate oil films on the moving parts of the machine.

(b) to achieve a great reduction in mechanical feed.

The accompanying drawings are:

Figure 1, a plan view of the microtome;

Figure 2, an elevation of same;

Figure 3, a detailed isometric view of the leaf spring mount;

Figure 4, a vertical section thru the main feed tube assembly on line 4, 4.

The microtome feed tube assembly as shown in Figure 4, consists of metal tube 18, rigidly held and supported in block 19, by the pressure of nut 24, being pushed by the plate 20, which in turn is held in place by screws 21. The knurled feed screw 17, rotates in nut 24, and bears upon thrust bearing 22. This action compresses spring 23, which stresses tube 18. When tube 18 is stressed, its deformation is proportional to the stress as long as the stresses applied are within the elastic limit of the material. This holds true for extremely small increments as well as large ones.

By using various pitched threads and nuts, and springs of different rates, a great variation in feed is possible. It is also possible to use hydraulic cylinder for applying the load to the spring 23. However, for increments of the size for which this machine was designed, the spring 23, can be compressed readily enough with screw 17.

The whole feed tube assembly Fig. 4, is mounted upon two leaf springs 1, as shown in Fig. 3. These springs avoid the use of conventional pivots with the associated play in such pivots. The leaf springs 1, are clamped to the feed tube support block 19, by blocks 2, held in place

2

by screws 3. The other ends of the leaf springs 1 are clamped to upright supports 4 by blocks 6, held in place by screws 5.

The normal equilibrium position of the leaf springs 1 holds the tube 18, horizontal. When a section is to be cut, the specimen 11 is held to collet 16. The knurled screw 17 is rotated the desired amount which causes tube 18 to elongate as per the description above.

By pressing down on the knurled collet 16 the specimen 11 describes an arc with the leaf springs 1 acting as pivots. This arc movement passes specimen 11 over the edge of the knife blade 10 causing a section to be cut off. When the downward force is removed, the leaf springs 1 return the tube assembly to the horizontal position again.

Uprights 4, are part of base 25. Coarse knife feed block 14 and fine knife feed block 12 are standard dovetail type ways with adjusting screws 15, and 13. Knife blade 10 is held by blade holder 9 and clamp 8 and tightening screw 7. Items 12, 13, 14, 15, and 7, 8, 9, 10 are standard machine details and are not claimed as part of the invention.

Therefore, I claim:

1. A micro-positioning assembly comprising a base, a tube mounted on the base and having on one end thereof a specimen-holding member and on the other end thereof a threaded member, a coiled spring within the tube, and a manually rotatable second threaded member engaging the first threaded member and abutting against one end of the spring to compress the spring, whereby the specimen-holding member is varied in position in microscopic amounts with respect to the base by the stress, such variation being linear with the rotation of the threaded member.

2. A micro-positioning assembly comprising a base, an elongated member mounted on the base and having on one end thereof a specimen-holding member and on the other end thereof a threaded member, a manually rotatable second threaded member engaging the first threaded member and a spring acting between the second threaded member and the specimen-holding member, whereby the specimen-holding member is varied in position in microscopic amounts with respect to the base by the stress, such variation being linear with the rotation of the threaded member.
